UNITED STATES PATENT OFFICE.

CHARLES J. SCHIPPLOCK AND JACOB C. KESSLER, OF CHICAGO, ILLINOIS.

PIE CUTTER.

Application filed March 10, 1921. Serial No. 451,107.

To all whom it may concern:

Be it known that we, CHARLES J. SCHIPPLOCK and JACOB C. KESSLER, citizens of the United States, residing at Chicago, in the county of Cook and State of Illinois, have invented new and useful Improvements in Pie Cutters, of which the following is a specification.

This invention relates in general to cutters, and has more particular reference to a cutter designed for cutting pies, cakes, and other similar objects or articles, into a number of equal pieces.

In restaurants, hotels, and other places where large numbers of pies must be cut daily, the time required to cut with a knife such a large number of pies is of considerable importance, and furthermore, the pieces of pie cut with a knife are apt to be unequal in size unless a guide be employed, and furthermore, the cut being made diametrically or radially of the pie, the crust is broken and the pieces present a rough and jagged appearance.

One of the primary objects of our present invention is to provide a cutter which, upon the actuation of an operating lever, will cut a pie, cake, or the like, simultaneously into the requisite number of pieces, thus greatly reducing the time which is customarily required to effect this result.

Another object of the invention is to provide a device in which the knives will cut through the pie from top to bottom instead of radially or diametrically thereof, thus producing a clean cut without breaking or otherwise injuring the crust so as to detract from the smooth and attractive appearance of the pieces.

A further object is to provide a device in which the cutting knives are readily detachable so that they may be quickly cleaned and replaced, and may also be replaced by differently shaped knives for cutting pies of different sizes, or which are contained in differently shaped tins, plates, or containers.

A further feature of our invention resides in its simplicity of construction, its cheapness of manufacture, its durability in use, and the ease and rapidity with which it may be operated.

Other objects and advantages of this invention will be readily appreciated, as the same becomes better understood, by reference to the following description, when con-

sidered in connection with the accompanying drawings.

Referring to the drawings:

Fig. 1 is a plan view of a pie cutter embodying our invention; and

Fig. 2 is a side elevation thereof.

By reference to the drawings, it will be observed that the apparatus comprises a base 3 in the form of a board or block of suitable dimensions, upon which a plate or tin containing the pie or cake to be cut, may be placed. This base is provided at each side with upwardly projecting guiding posts 4 rigidly secured to the base by nuts 5 and 6, or other suitable fastening means. Between these posts, there is disposed a carrying head comprising a disc 7 preferably provided with a circumferential upstanding flange 8, and equipped with radially projecting arms 9 riveted or soldered to the upper face of the disc, these arms being upturned, as indicated at 11, and their extremities bent inwardly at 12 and the portions 9 and 12 being provided with aligned apertures adapted to slidably fit the posts 4 whereby the head is slidably but securely mounted upon the posts.

The central portion of the disc may be cut away, as indicated by reference character 13, and preferably, the two arms 9 are integrally connected by an upstanding yoke or bail 14 adapted to be engaged by a hand lever 15 pivoted upon a bolt 16, carried by a pair of standards 18, which are mounted on the base 3 near one side thereof. By pressing downwardly upon the free end of the lever 15, the head will obviously be forced downwardly, being guided in its movements by the posts. 4.

The under side of the disc is equipped with a plurality of knife holders 19, these holders being riveted or otherwise secured to the under face of the disc, and each comprising a channel-shaped member having a longitudinally extending slot in its lower face of substantially the width of the knife blades to be carried in the holders. These holders are radially arranged on the disc, and any desired number may be employed, although in the present instance, we have shown five adapted to cut a pie into five pieces.

A similar number of cutting blades 21 is employed, each blade being provided at its upper edge with a T-shaped supporting por-

tion 22 adapted to slidably engage in a holder 19. The inner edges 23 of the blades are inclined toward a common center so that their points are disposed in proximity to each other, as shown in Fig. 2, and their cutting edges each comprise a straight line portion 24 of substantially the same length as the radius of the bottom of the pie tin, a curved portion 25 conforming to the curvature of the pie tin flange, and a short straight portion 26 adapted to engage the marginal flange of the tin. It will be apparent therefore, that the contour of the cutting edge of each blade conforms substantially to the contour of the pie tin so that when the blade is forced downwardly into the tin, it will cut the bottom crust from the center of the pie to the margin overlying the flange of the tin.

20 Since the cutting blades are merely slid longitudinally into their respective holders, it will be manifest that they are detachably carried thereby and may be quickly and easily removed for washing, and may be readily replaced. Furthermore, to adapt the machine for pies of various sizes, blades of different lengths may be supplied with each machine, and one set of blades may be removed and replaced by another for cutting different sized pies. Obviously, also, the shape of the cutting edges of the blades may be varied to conform to pie tins of different contours.

25 The head, with the knives carried thereby, is normally retained in the elevated position shown in Fig. 2 by a plurality of coiled expansion springs 27 surrounding the posts 4 between the base and the arms 9, so that normally, the head is retained in the elevated position to permit a pie to be positioned under the head.

It will be apparent from the foregoing that we have provided a device by which pies can be quickly, smoothly and economically cut. In order to cut a pie, it is only necessary to place the same on the base beneath the cutter head and depress the outer end of the operating lever, thus forcing the knives downwardly through the pie from top to bottom, cutting it into the desired number of pieces at one movement. Upon release of the lever, the springs return the parts to normal position, whereupon the pie may be slid off from the base and replaced by another.

55 It is believed that our invention, its construction, mode of operation, and many of its advantages will be understood and appreciated from the foregoing without further description, and obviously, the details 60 of construction shown and described may be varied within wide limits without exceeding the scope of the invention, as defined in the appended claim.

65 We claim:

In a pie cutter, the combination with a base, of a pair of vertical standards projecting upwardly from said base, a slidable head mounted on said standards, said head including a horizontally disposed disk, radial knife holders carried by said disk, knives detachably supported by said holders and projecting toward said base, springs surrounding the standards and normally urging said disk upwardly, an upright disposed at one side of the disk, a handle pivoted to said upright, and a yoke carried by said disk and projecting thereabove adapted to be engaged by said handle to lower the disk against the tension of said coil springs. 75

CHARLES J. SCHIPPLOCK.

JACOB C. KESSLER.
